RIBBED METAL PANEL

Donald H. Landis, Pittsburgh, and Richard C. Pfaff,
Murrysville, Pa., assignors to Epic Metals Corporation,
Braddock, Pa.

Filed Jan. 15, 1973, Ser. No. 323,912

Term of patent 14 years

Int. Cl. D25—01

U.S. Cl. D54—2 A

FIG. 1 is a perspective view of a ribbed metal panel showing one embodiment of our new design.

FIG. 2 is an end view of the panel of FIG. 1 showing the rib profiles and connecting panel portions.

FIGS. 3 and 4 are end views similar to FIG. 2, but showing other embodiments of our new design.

We claim:

The ornamental design for a ribbed metal panel, substantially as shown and described.
